UNITED STATES PATENT OFFICE

112,792

DESIGN FOR A SHOE OR SIMILAR ARTICLE

Edward P. Schmidt, Milwaukee, Wis., assignor to
Racine Shoe Manufacturing Company, Racine,
Wis., a corporation of Wisconsin

Application February 16, 1938, Serial No. 75,179

Term of patent 7 years

To all whom it may concern:

Be it known that I, Edward P. Schmidt, a citizen of the United States, residing at Milwaukee, in the county of Milwaukee and State of Wisconsin, have invented a new, original, and ornamental Design for a Shoe or Similar Article, of which the following is a specification, reference being had to the accompanying drawing, forming part thereof.

In the drawing:

Fig. 1 is a plan view of the shoe or similar article showing my new design; and

Fig. 2 is a side elevational view slightly in perspective.

The characteristic features of the present de-

sign reside in the shape of the complementary strap members, both sides of each strap member diverging along substantially straight lines at the top of the tongue of the shoe to produce spaced bell shaped portions stitched to the tongue of the shoe and having substantially parallel edges which are connected by mock lacing, in combination with a shoe having a central longitudinal seam which extends between the spaced portions of said strap members.

I claim:

The ornamental design for a shoe or similar article, as shown and described.

EDWARD P. SCHMIDT.
